UNITED STATES PATENT OFFICE.

JOHN W. GURLEY, OF INDIANAPOLIS, INDIANA.

ROTARY PUMP.

Application filed February 10, 1925. Serial No. 8,259.

It is the object of my invention to produce a pump of the type in which a rotor provided with a plurality of retractible blades rotates within an eccentric chamber so that spaces between two adjacent blades, the rotor, and the chamber walls alternately increase and diminish in size. Specific objects of my invention are to lessen the wear and friction loss in such a pump and to provide means for preventing scoring of the chamber wall or rotor surface owing to grit or other foreign substances which enter the pump. A further object of my invention is to increase the capacity of such a pump by using the reciprocation of the blades in their slots to aid in the pumping action.

I accomplish the above objects by providing in the exterior face of each blade a rocking shoe which engaging the inner surface of the pump chamber and which is provided in its outer face with a recess which has two openings, one of such openings being in the outer face of the blade to provide communication between the recess and the space ahead of such blade in the direction of rotor rotation, and the other of which openings communicates through an opening in the blade with the space behind such blade. Ahead of each blade in the direction of rotation I provide in the surface of the rotor a longitudinally extending groove in which will be accumulated any grit or other foreign substance which may enter the pump.

The accompanying drawing illustrates my invention: Fig. 1 is a longitudinal central section of the pump on the line 1—1 of Fig. 2; Fig. 2 is a transverse section of the pump on the line 2—2 of Fig. 1; Fig. 3 is a perspective view of one of the blade shoes used; and Fig. 4 is a perspective view of one of the reciprocating blades.

My pump comprises a casing 10 provided with an inlet opening 11, an outlet opening 12, and a longitudinally extending cylindrical chamber 13. Mounted on each end of the casing 10 is an end plate 14, preferably provided with a bearing boss 15 to provide a bearing for the rotor shaft 16. The rotor shaft 16 extends longitudinally of

the casing and passes through the chamber 13, but is not co-axial with such chamber. On its outer end, the shaft 16 may be provided with a pulley 17 for the purpose of driving it.

A passage 20, located on the wall of the chamber 13, serves to connect the inlet opening 11 with a recess 21 located in one or both of the end plates 14. These recesses 21 extend toward the center of the chamber 13 and serve to connect the chamber 13 with the inlet opening 11 through the longitudinally extending passage 20. A second longitudinally extending passage 22, located in the wall of the casing, preferably opposite the passage 20, communicates with a recess 23 in one or both of the end plates 14. The recess or recesses 23 are similar to the recess or recesses 21 and serve to connect the chamber 13 with the outlet opening 12 through the passage 22.

Within the chamber 13, there is rigidly mounted on the shaft 16 a cylindrical rotor 25. In the surface of the rotor 25 there are a plurality of grooves in each of which there is slidably mounted a blade 26. Preferably, these grooves are arranged in pairs with the grooves of each pair diametrically opposite each other. Extending between opposite grooves is one or more holes for the reception of pins 27 rigidly attached to each blade 26. The pins 27 are of such a length that opposite pins abut each other when the blades to which they are attached most closely approach each other.

The outer surface of each of the blades 26 is provided with a groove 28 for the reception of a rocking shoe 30, the inner surface of such shoe being shaped to fit the groove 28, and the outer surface of such shoe being a portion of a cylindrical surface of a radius equal to that of the chamber 13. Thus, the outer surface of each shoe 30 will always be firmly seated against the wall of the chamber 13, the shoe rocking in its seat as the rotor revolves. The outer face of each shoe has a recess 31 which communicates through an opening 32 with the space ahead of such shoe in the direction of rotation. The forward face of each blade 26 may be

provided with a notch 33, in line with the opening 32. From the bottom of each recess 31 there extends through the shoe a hole 34 which communicates with a hole 35 passing through the associated blade 26.

In the surface of the rotor, ahead of each blade, I provide a longitudinally extending groove 38. Grit or foreign substances which enter the pump tend to become wedged between the rotor and the wall of the chamber 13 at the point where the rotor most closely approaches such wall. The grooves 38 serve as pockets in which such grit may be deposited and thus removed from the surface of the rotor or the wall of the chamber. The removal in this fashion of any grit that may enter the pump prevents scoring the surfaces of the rotor and chamber wall.

The blades 26 and shoes 30 serve to divide into four parts the space between the rotor and the walls of the chamber 13. With the rotor rotating in a clockwise direction (Fig. 2), the spaces between adjacent blades on the right-hand side of the rotor will be expanding and those on the left-hand side of the rotor will be contracting. Thus, fluid will be drawn in through the inlet opening 11, passage 20, and recesses 21 to fill the expanding spaces on the right side of the rotor, and this fluid will be expelled by the contraction of such spaces when they reach the left-hand side of the pump. This is the manner in which all pumps of this type operate. By my improved construction, however, the reciprocation of the blades themselves is used to increase the capacity of the pump, for the space between each blade and the bottom of the groove in which it is received is expanding when such space is in communication with the recesses 21 and is contracting when such space communicates with the recess 23. Thus each blade operates in the manner of the piston of a reciprocating pump. The pressure between each blade and the bottom of its groove is communicated through the holes 34 and 35 to the recesses 30 in the face of the blade shoe, and the pressure in the recess 31 serves to partially balance that beneath each blade. Thus, the force with which each blade shoe is pressed against the wall of the chamber 13 is materially reduced and wearing of the shoe surface and friction loss is correspondingly diminished. The holes 34 and 35 and the opening 32 provide a passage for the fluid forced out from the space between each blade and the bottom of its groove.

I claim as my invention:—

1. In a rotary pump having a shell, a rotor eccentrically mounted in said shell, retractile blades carried by said rotor; wearing shoes mounted in said blades and engaging said shell, said wearing shoes having recesses in their shell-engaging faces, each of said recesses communicating with the space be-

tween said rotor and said shell and immediately ahead of said shoe in the direction of rotation of said rotor.

2. In a rotary pump having a shell, a rotor eccentrically mounted in said shell, retractile elements carried by said rotor and engaging said shell, said retractile elements having recesses in their shell-engaging faces, each of said recesses communicating with the space between said shell and said rotor and immediately ahead of said element in the direction of rotor rotation.

3. A rotary pump, comprising a shell, a rotor rotatably mounted in said shell, a plurality of retractile elements mounted on said rotor and engaging said shell, said shell being arranged so that the spaces between it, said rotor, and adjacent retractile elements will alternately increase and decrease in size as said rotor is rotated, an inlet opening and an outlet opening for said shell, each of said retractile elements having a recess in its shell-engaging face, each of said recesses communicating with the space between said shell and said rotor and immediately ahead of said element in the direction of rotor rotation.

4. A rotary pump, comprising a shell, a rotor rotatably mounted in said shell, a plurality of retractile blades mounted on said rotor and engaging said shell, said shell being arranged so that the spaces between it, said rotor, and adjacent retractile blades will alternately increase and decrease in size as said rotor is rotated, an inlet opening and an outlet opening for said shell, a wearing shoe mounted in each of said blades and engaging said shell, each of said wearing shoes having a recess in its shell-engaging face, each of said recesses communicating with the space between said rotor and said shell and immediately ahead of said shoe in the direction of rotation of said rotor.

5. A rotary pump, comprising a shell having inlet and outlet openings, a rotor rotatably mounted in said shell and having a plurality of longitudinal grooves in its face, shell-engaging elements mounted in said grooves for radial sliding therein, said shell being arranged so that said shell-engaging elements slide inwardly and outwardly in said grooves as said rotor is rotated, and a fluid passage through said shell-engaging element connecting the space between such element and the bottom of its associated groove with the space between said rotor and said shell and immediately ahead of such element in the direction of rotor rotation.

6. A rotary pump, comprising a shell having inlet and outlet openings in the ends thereof, a rotor rotatably mounted in said shell and having a plurality of longitudinal grooves in its face, shell-engaging elements mounted in said grooves for radial sliding therein, said shell being arranged so that

5 said shell-engaging elements slide inwardly and outwardly in said grooves as said rotor is rotated, and a fluid passage connecting the space between such element and the bottom of its associated groove with the space between said rotor and said shell and immediately ahead of such element in the direction of rotor rotation.

7. A rotary pump as set forth in claim 5 10 with the addition that said shell-engaging elements are provided with recesses in their shell-engaging faces, said fluid passage leading through said recesses.

8. A rotary pump, comprising a shell having 15 inlet and outlet openings, a rotor rotatably mounted in said shell and having a plurality of longitudinal grooves in its face, shell-engaging elements mounted in said grooves for radial sliding therein, said shell 20 being arranged so that said shell-engaging elements slide inwardly and outwardly in said grooves as said rotor is rotated, each of said shell-engaging elements having a recess in its shell-engaging face, and a fluid passage 25 connecting said recess with the space between each shell-engaging element and the bottom of its associated groove.

9. A rotary pump, comprising a shell having 30 inlet and outlet openings, a rotor rotatably mounted in said shell and having a plurality of longitudinal grooves in its face, blades mounted in said grooves for radial sliding therein, said shell being arranged so that said blades slide inwardly and outwardly in said grooves as said rotor is rotated,

wearing shoes mounted in said blades and engaging said shell, each of said wearing shoes having a recess in its shell-engaging face, and a fluid passage connecting said recess with the space between its associated 40 blade and the bottom of the groove in which said blade slides.

10. In a rotary pump having a shell, a rotor eccentrically mounted in said shell, retractible blades carried by said rotor; wearing shoes mounted in said blades and engaging said shell, said wearing shoes having recesses in their shell-engaging faces. 45

11. A rotary pump, comprising a shell having inlet and outlet openings, a rotor 50 rotatably mounted in said shell and having a plurality of longitudinal grooves in its face, shell-engaging elements mounted in said grooves for radial sliding therein, said shell being arranged so that said shell-engaging elements slide inwardly and outwardly in said grooves as said rotor is rotated, said inlet opening being arranged to communicate with each of said grooves through the end thereof as the shell-engaging 55 element in such groove slides outwardly, and said outlet opening being arranged to communicate with each of said grooves through the end thereof as the associated shell-engaging element slides inwardly. 60 65

In witness whereof, I have hereunto set my hand at Indianapolis, Indiana, this 30th day of January, A. D. one thousand nine hundred and twenty five.

JOHN W. GURLEY.
